DECORATIVE HEATING PAD

Betty Joan Durr, 429 W. 45th St.,
New York, N.Y. 14301

Filed Nov. 12, 1965, Ser. No. 88,078

Term of patent 14 Years

(Cl. D83—1)

FIG. 1 is a front view of a decorative heating pad showing my new design.

FIG. 2 is a rear view thereof.

FIG. 3 is a side view thereof.

I claim:

The ornamental design for a decorative heating pad, as shown.
